DESIGN FOR A BATHING CAP

Jeannette M. Witkins, New York, N. Y.

Application October 31, 1940, Serial No. 96,243

Term of patent 7 years

To all whom it may concern:

Be it known that I, Jeannette M. Witkins, a citizen of the United States and a resident of the city of New York, in the county of New York and State of New York, have invented a new, original, and ornamental Design for a Bathing Cap, of which the following is a specification, reference being had to the accompanying drawing, forming a part thereof.

Fig. 1 is a front elevational view of a bathing cap showing my new design as it appears when worn.

Fig. 2 is a front elevational view thereof as

it appears when not on the head of the wearer.

Fig. 3 is a side elevational view of Fig. 1.

Fig. 4 is a rear elevational view of Fig. 1.

The characteristic feature of my design resides in a bathing cap having the configuration of a hairdress forming, at the lower portions thereof, a loose-hanging smooth-lying member for retaining the hair and extending around the back and sides as shown.

I claim:

The ornamental design for a bathing cap, substantially as shown and described.

JEANNETTE M. WITKINS.
